UNITED STATES PATENT OFFICE.

SANFORD S. BURR, OF WINNETKA, ILLINOIS.

SPRING BED-BOTTOM.

SPECIFICATION forming part of Letters Patent No. 296,672, dated April 8, 1884.

Application filed October 10, 1883. (No model.)

To all whom it may concern:

Be it known that I, SANFORD S. BURR, a citizen of the United States, residing at Winnetka, in the county of Cook and State of Illinois, have invented certain new and useful Improvements in Spring Bed-Bottoms, of which I do declare the following to be a full, clear, and exact description, reference being had to the accompanying drawings, forming part of this specification.

In an application for Letters Patent filed of even date herewith I have described and claimed improved means whereby the springs of bed-bottoms can be readily adjusted to compensate for any irregularities or depressions due to the sagging of the cover of the bottom. In the invention set out in said application the adjustment of the springs and cover of the bed-bottom was affected by straightening 20 the supporting strips or rods upon which the springs rested, and thus the springs at such portion of the bed-bottom as had become irregular or depressed might be easily lifted.

My present invention also has for its object 25 the provision of means whereby the springs of bed-bottoms may be readily adjusted to compensate for the permanent depression of the springs and sagging of the cover incident to long or severe usage; but in this case the strips or rods that support the springs are 30 provided with means whereby they can be lifted vertically, so that whether the strips or rods be flexible, as in the application above referred to, or be stiff, the desired adjustment 35 of the springs can be easily effected.

In the accompanying drawings, Figure 1 is 40 a view in vertical longitudinal section of a spring bed-bottom to which my invention has been applied. Fig. 2 is a view in vertical transverse section, and Fig. 3 is an inverted plan view, of such bed-bottom. Fig. 4 is a detail enlarged view in section, showing a modified form of sustaining-bolt for the spring-supporting strips.

45 A designates the side bars, A' the end bars, and A² the top bars, of the bed-bottom, over which is stretched the cover A³, preferably of woven wire, having its ends held firmly by the clamp-strips a, secured to the top bars of the 50 main frame. Through the top bars, A², and held therein by heads b and washers b', descend the bolts B, over the threaded ends of which fit the friction-washers b² and hand-nuts

b³, which serve to support and retain in place the spring-sustaining bars C, through the slots 55 or eyes c in the ends of which the bolts pass. These bars C are preferably of thin elastic wood or metal, and may be of any desired number. Upon the bars C rest the slats D, to which are attached the spiral springs e, of 60 usual construction, which bear against the under side of the woven-wire cover, and serve to keep the same tightly stretched.

When from any cause, as by long or severe usage, the springs become permanently depressed and the cover slack and irregular, the supporting-bars D can be readily lifted by turning the hand-nuts b², thus readily adjusting the springs and the cover to their proper position. The bars A not only serve as adjustable supports for the springs, but, being of yielding material, serve the further function of giving greater elasticity to the bed-bottom. By providing the supporting-bars with the means shown for vertical adjustment 75 the springs can be pressed constantly against the cover to uniformly stretch the same.

In Fig. 4 is illustrated a slightly-modified form of this invention, wherein the bolts B are hinged, as at x, to allow greater freedom 80 of movement to the supporting-bars.

Having thus described my invention, what I claim as new, and desire to secure by Letters Patent, is—

1. In a spring bed-bottom, the combination, 85 with the frame and the cover, of the springs located beneath said cover, the longitudinal sustaining-slats for said springs, and adjusting mechanism, arranged substantially as set forth, whereby said sustaining-slats can be 90 lifted vertically in order to vary the tension of the springs, substantially as described.

2. In a spring bed-bottom, the combination, 95 with the frame and the cover, of the springs located beneath said cover, the transverse slats for said springs, the longitudinal slats, and means, substantially as described, for adjusting said spring-sustaining slats vertically, whereby the tension of the springs can be varied, substantially as described.

In testimony whereof I have hereunto set my hand,

SANFORD S. BURR.
